UNITED STATES PATENT OFFICE.

RICHARD C. NUGENT, OF PITTSBURG, PENNSYLVANIA, ASSIGNOR OF FIVE-EIGHTHS TO W. J. ARMSTRONG, THOMAS T. WIGHTMAN, JOHN FARRELL, AND JOS. G. WAINWRIGHT, OF SAME PLACE.

FLANGING-MACHINE.

SPECIFICATION forming part of Letters Patent No. 291,620, dated January 8, 1854.

Application filed February 5, 1853. (No model.)

To all whom it may concern:

Be it known that I, RICHARD C. NUGENT, a citizen of the United States, residing at Pittsburg, in the county of Allegheny and State of Pennsylvania, have invented certain new and useful Improvements in Machines for Flanging Metal Plates of Regular or Irregular Form, of which the following is a full, clear, and exact description.

The object of my invention is to build a machine which shall be capable of flanging metal plates of regular or irregular outlines, and shall at the same time be so constructed as that the great strain necessarily borne by it shall be evenly distributed between the various parts.

The invention consists in the hereinafter described means for attaining said object.

In the accompanying drawings, Figure 1 represents a vertical section of my machine; Fig. 1^a represents a top view of my machine; Fig. 2, a detail view of the segmental roller-bearing rack; Fig. 3, a side elevation of one of the segmental arms; Fig. 4, a detail plan view of the large gear-wheel and its arms; Fig. 5, detail views of pattern-forms of different outlines.

Similar letters of reference indicate corresponding parts throughout the various views.

A represents the bed-plate of the machine, near the periphery of which are secured the lower extremities of three curved housings, B. The upper ends of these housings are fast in the annular nut C.

To the center of the bed-plate A is bolted the pillar D, which has secured to its top the table E, the latter carrying the metal plate while being flanged. Said plate is held rigidly in place by the clamp-plate F, which is borne by a screw, G, passing through the aforementioned annular nut C. The free end of the screw is provided with a hand-wheel or other like device, by turning which the clamp-plate F is raised or lowered.

Revolving about the pillar D as an axis is a large bevel-gear wheel, H, provided with two slotted arms, H'. These arms extend outwardly to the housings B, and revolve in a circular guide-ring, H², bolted to said housings.

Secured to the bed-plate A are three small

pillars, I, and bolted to the tops of these pillars is the pattern-form K. Said pattern-form is constructed with guideways or grooves k for the purpose hereinafter specified.

Upon the upper sides of the arms H' and lengthwise of the same, guides h are bolted, and in these guides slide the base-plates of the segmental arms L. Extending downward from said arms L, through the slots in arms H', and into the grooves or guideways of the forming-pattern K are pins l, carrying anti-friction rollers. From this construction it will be seen that as the gear-wheel H and the arms H' revolve, the pins l carrying anti-friction rollers will follow the guideway of pattern K, and the segmental arms L will slide toward or from the pillar D, according to the form of the pattern K.

Sliding in guides formed in the segmental arms L are the segmental racks L'. Said racks are provided on their outer edges with teeth, which register with worms M borne by shafts M'. Said shafts are journaled near their lower ends in rocking bearings M², and their upper ends are supported in eccentrically-movable journal-bearings m'. The latter move in extensions m of arms L, and are provided on their upper extremities with hand-levers m², by means of which the worms M are thrown in or out of engagement with the racks L'.

Attached to the lower extremities of the shafts M' are pinions m³, and these pinions gear with a segmental toothed rack, N, borne by slide-rod N' working through openings in the housings B. Said slide-rod is secured in any desired position by means of pin n passing transversely through the housings B. The object of this rack is to actuate the pinions m³, and, through the medium of the shaft M' and worm M, to raise the segmental racks L'.

Revolving upon spindles secured in the rack L' are the fixed cylindrical rollers O, and revolving upon other pins or spindles, secured in the swinging plate or arm P, are the movable rollers O'. This plate or arm P swings upon a pivot secured in the outer end of the rack L', and is fixed in its normal position by a pin, p, passing through it and the rack L'. The object of this construction is to allow the rolls O' to swing outward and avoid contact

with the metal plate operated upon when the rack L' is lowered after the plate has been flanged, and also to allow a new plate to be inserted after the one already operated upon 5 has been removed.

The whole machine is actuated by a bevel-gear wheel, R , meshing with the bevel-gear wheel H , and borne by the driving-shaft S . The latter has bearings in one of the pillars I 10 and housings B .

The operation of my machine is as follows: The pattern-form K having been bolted upon the pillars I , and the metal blank to be operated upon having been clamped upon the table 15 E by means of the clamping device $G F$, the driving-shaft S is put in motion. By this means the arms H' are caused to revolve, and the pins l , carrying anti-friction rollers of the segmental arms L , following the guideway of 20 the pattern-form K , causes the said arms L to slide toward or from the pillar D , and the rollers $O' O'$ to describe a path similar in outline to the guideway of the pattern-form, and thereby flange the metal blank in like outline.

25 Contemporaneously with the above operation, the pinions m^2 have at intervals engaged with the segmental rack N , said segmental rack being moved from time to time in order to engage with said pinion, and the rollers $O' O'$ have, through the medium of the shafts M' , worms M and rack L' , been thereby turned upward until the flange upon the metal blank 30 has attained the desired angle.

It will be understood that if the pinions m^2 35 catch or mesh with the rack N to the extent of three or four teeth, the amount of elevation of rack L' necessary to the proper flanging of the plate is fully complied with, and this for the reason that the engine runs faster 40 or slower, as the distance or amount of friction, &c., to be overcome is greater or less. The flanging of the metal blank being now completed, the pins p are removed from the swinging arms or plates P , in order to allow 45 the rollers O' to swing outwardly. The worms M are then thrown out of engagement with the racks L' by turning the levers m^2 attached to the eccentrically-movable journal-bearings m' . Said racks L' are then lowered, the flanged

plate removed and another inserted, the pins 50 p and the worms M reinstated, and the machine is ready to operate upon another blank.

It will be seen that in case a differently-shaped pattern-form is inserted the rack N must be moved inward or outward, as the case 55 may be, to gear with the pinions m^2 . This is done by means of the slide-rod N' , and said rack is fixed in the desired position by inserting the pin n in place.

It may be added that for purposes of convenience the pattern-forms are usually made in two pieces, they being in that shape more readily and conveniently applied to and secured upon the pillars I .

Having thus described my invention, what I 60 claim is—

1. In a flanging-machine having revolving slotted arms, the combination of the guide-pattern K with the roller-bearing arms L , provided with pins l , substantially as described, 70 whereby the rollers are made to describe the outline of the pattern, for the purposes set forth.

2. The combination, with the racks L' , the arms L , and the shafts M' , of the eccentrically-movable journal-bearings with attached levers m^2 , substantially as described, whereby 75 the racks and worms are thrown out of gear, for the purposes set forth.

3. The combination, with the fixed rollers 80 O and the racks L' , of the movable rollers O' , pivoted plates P , and pins p , substantially as described, whereby the rollers O' may be locked or swung out of place, for the purposes set forth.

4. The within-described machine for flanging metal plates of regular or irregular form consisting, essentially, of housings B , pillar D , wheel H , having slotted arms H' , pillars I , guide-pattern K , arms L , toothed racks L' , 90 rack N , and clamp F , all provided with operating mechanism, and arranged in the manner and for the purposes set forth.

RICHARD C. NUGENT. [L. S.]
